MAINE.

AIR-CHEST.

1,173,404.

Specification of Letters Patent. Patented Feb. 29, 1916.

Application filed May 3, 1915. Serial No. 25,370.

To all whom it may concern:

Be it known that we, JOHN T. AUSTIN and BASIL G. AUSTIN, citizens of the United States, residing at Hartford, in the county 5 of Hartford and State of Connecticut, have invented certain new and useful Improvements in Air-Chests, of which the following is a specification.

This invention relates to air-chests, the 10 object of the invention being to provide a device of this character having means associated therewith, which is positive and certain in action and by which the supply of air from a pump or its equivalent to such 15 chest can be effectively and precisely controlled.

While an air-chest involving the invention can be employed with advantage in many different connections, it is of especial 20 utility when incorporated in or forming part of a pipe organ.

In the drawings accompanying and forming part of the present specification we have shown in detail one of the several convenient 25 forms of embodiment of the invention which to enable those skilled in the art to practice the same will be set forth fully in the following description. We do not restrict ourselves to this disclosure; we 30 may depart therefrom in several respects within the scope of the invention defined by the claims following said description.

Referring to said drawings: Figure 1 is a vertical sectional view of an air-chest and 35 coöperating elements involving our invention, showing the pump as cut off from the air-chest. Fig. 2 is a similar view with the pump supplying the air-chest.

Like characters refer to like parts in both 40 views.

The numeral 2 denotes an air-chest, 3 a pump and 4 a duct connecting the pump with the air-chest, all suitable for our purpose. Inclosed by the duct or supply pipe 45 4 is a valve 5 shown as being of "butterfly" type. In Fig. 1 the valve is closed so as to cut off communication between the pump 3 and the air-chest 2. In Fig. 2 the valve is shown open so as to put the pump into communication with said air-chest and in the 50

latter event to permit the supply of compressed air from the pump to the air-chest. In said air-chest 2 is mounted a pneumatically-governed member as the bellows 6, the chest having ports 7 and 8 opening from the 55 atmosphere into the interior of the bellows 6. Between the chest 2 and the movable board 9 of the bellows and inclosed by the latter is a spring device as 10 which tends constantly to expand the bellows 6 or to 60 move the board or body 9 thereof inward. To the body or board 9 of the bellows is connected the stem or shank 11 of the valve 12, this shank or stem being fastened to the inner face of the board or body 9 within 65 the bellows. The valve controls one end of the tube 13 extending into the chest 2, the other end of said tube having an enlarged head 14 fitted over the tubular projection 15 extending laterally from the duct 4 between the ends thereof. The head 14 and the tubular extension 15 present a cylindrical chamber and they clamp the marginal, flexible portion of the diaphragm member 16. To the central or body part 70 of said diaphragm member is pivotally connected the link 17 extending inward from said body part of the diaphragm member and likewise jointed to the crank arm 18 of the valve 5. The body or core part of 80 the diaphragm member 16 has a bleed opening 19. Connected to the valve 5 is a spring 20 which tends constantly to close said valve. Connected with the board 9 and extending outward therefrom is the stop-member 21 projecting through the opening or port 8 and the head 22 of which engages the outside of the air-chest 2 when the port 9 is in normal position as shown in Fig. 2.

In Fig. 2 the valve 5 is wide open and the 90 bellows 6 in its expanded condition, where it is held by the spring 10, the valve 12 at this time uncovering the upper open end of the tube 13. The consequence is that said tube 13 will be in communication with the 95 atmosphere by way of the ports or openings 7 and 8. The diaphragm-member, pouch or pneumatic 16 is shown as being in the outer position where it is held by the pressure of air against the inner side there- 100

of. The pump 3 is assumed to be in action and to be supplying compressed air to the chest 2 by way of the duct 4. One side of the diaphragm member 16 is presented to the atmosphere, the other side as noted being exposed to pressure by virtue of which the valve 5 will be maintained in open position by the pressure. After a predetermined amount of air is in the chest 2, the part 9 of the bellows 6 is moved to cause the valve 12 to close the adjacent end of the tube 13, thereby cutting off the diaphragm member 16 from the atmosphere. When this occurs compressed air passes into the tube 13 by way of the bleed opening 19 and when the pressure against opposite sides of the diaphragm 16 are balanced, the spring 20 becomes effective for instantly shutting the valve 5 and the valve will be maintained in shut relation as shown in Fig. 1 to cut off communication between the pump 3 and the air chest 2 until the amount of air in the air-chest has been reduced sufficiently to permit the spring 10 to move the part 9 inward and cause the valve 12 to uncover the upper end of the tube 13. At this point the outer surface of the diaphragm member 16 will be presented again to the atmosphere, so that the pressure in the duct 4 above the valve 5 can act against said diaphragm member 16 to move the same outward and thereby through the link 17 and crank arm 18 swing the valve 5 open.

What we claim is:

35 1. The combination of an air chest, a pump for supplying air to the air chest, a device normally exposed to atmosphere on one side and exposed to pressure from the pump on the other side, a member operable by the pressure of the pump, means governed by said member, for cutting off communication of said device with the atmosphere, and means controlled by said device when cut off from the atmosphere for stopping the supply of compressed air to the air chest.

50 2. The combination of an air-chest, a pump for supplying air to the air-chest, a device normally exposed to atmosphere on one side and exposed to pressure from the pump on the other side, a member in the air-chest operable by the pressure therein, means governed by said member for cutting off communication of said device with the atmosphere, and means controlled by said device when cut off from the atmosphere for stopping the supply of compressed air to the air-chest.

55 3. The combination of an air-chest, a pump for supplying compressed air to the air-chest, a device normally exposed to atmosphere on one side and exposed to pressure from the pump on the other side, a member in the air-chest operable by the pressure therein, means governed by said

member for cutting off communication of said device with the atmosphere, a valve, and means controlled by said device when the latter is cut off from the atmosphere for shutting the valve to thereby stop the supply 70 of air from the pump to the air chest.

4. The combination of an air-chest, a pump for supplying air to the air-chest, a device normally exposed to atmosphere on one side and exposed to pressure from the 75 pump on the other side, means for shutting off communication between said device and the atmosphere at a predetermined point, and means controlled by said device when cut off from the atmosphere for stopping the 80 supply of air to the air-chest.

5. The combination of an air chest, a pump for supplying air to the air chest, a device exposed to atmosphere on one side and to pressure from the pump on the other 85 side, a member operable in one direction by the pressure of the pump, means for operating said member in opposition to the pressure of the pump, means governed by said member for cutting off communication of 90 said device with the atmosphere when said member is operated by pressure, and means controlled by said device when cut off from the atmosphere for stopping the supply of 95 compressed air to the air chest.

6. The combination of an air-chest, a pump for supplying air to the air-chest, a tube having an end opening to atmosphere, a device exposed to atmosphere on one side, by way of said tube and to pressure from 100 the pump on the other side, a member in the air-chest operable by the pressure therein, a valve connected with said member, for closing the atmosphere end of said tube through the action of said member at a pre-determined point, a valve between the pump and the air-chest and operatively connected with said device, and spring means for closing said second valve when said device is cut off from communication with the atmosphere. 110

7. The combination of an air-chest, a pump for supplying air to the air-chest, a valve for controlling communication between the air-chest and the pump, spring 115 means connected with the valve and tending constantly to close said valve, a chamber, a diaphragm member in the chamber, operatively connected with the valve, said diaphragm member having a bleed opening and 120 the chamber being in communication with the atmosphere, and means for cutting off communication between said chamber and the atmosphere at a predetermined point.

8. The combination of an air-chest, a 125 pump for supplying air to the air-chest, a valve for controlling communication between the air-chest and the pump, means tending constantly to close said valve, a chamber, a diaphragm member in the chamber, 130

ber, operatively connected with the valve, said diaphragm member having a bleed opening, a tube connecting the chamber with the atmosphere, a member in the air-chest, 5 and a valve connected with said member, said member being operable to cause the valve to close said tube when a predetermined amount of air is in the air-chest.

In testimony whereof we affix our signatures in presence of two witnesses. 10
